ABSTRACT OF THE DISCLOSURE

A multi-color press product, viewable by reflected and transmitted light comprising a first series of color impressions, a transparent material, and a second series of identical impressions respectively of colors identical with the impressions of the first series.

This application is a continuation-in-part of my application Ser. No. 297,557, filed July 25, 1963, now abandoned.

This invention relates to a transparency or the like with controlled body, and a method of producing the product. The invention has particular reference to the product of the multi-color printing press on which a number of colored impressions are printed sequentially and in perfect registry upon work which is fixed to the bed of the press during the successive printing operations. The invention seeks to provide a picture which will yield a brilliant image both in transmitted and reflected light.

Pictures printed in color on transparent or translucent webs or sheets frequently lack the intensity of pigment which would permit them to be viewed without loss of detail. The web or sheet has to have a certain amount of body to permit it to be handled as a transparency in commercial practice. Previous attempts to solve the problem have involved printing the desired image on the face of the sheet or web and then printing a registering image in reverse on the back of the web or sheet. Due to the required body and thickness of the web or sheet, diffusion results, particularly if the material is transparent. Even though the two images may be in full registry when the line of sight of a viewer is normal to the surface, all other portions of the picture suffer from offset, which reduces clarity or sharpness. Thus, completely ignoring the problem of securing perfect registry, even the best work in this regard does not yield the desired result.

The present invention is based on the discovery that both brilliance of color and sharpness of detail can be achieved if, while the work is still fixed to the bed of the press the otherwise finished picture produced by the first series of impressions is covered by a very thin translucent coating which serves as a base upon which the same sequence of impressions is repeated so that the composite picture is printed twice in the same sense and on the same side of the base sheet. Since the second image is identical with the first (instead of being the reverse thereof), each of the second series of impressions reinforces the effect of the corresponding impressions of the first series to give added depth of tone when the product is viewed as a transparency but without in any way modifying to any material degree the appearance of the work as viewed by reflected light.

In the drawings:

FIG. 1 is a diagrammatic illustration of a sheet printed with a first impression in accordance with a first method step of the present invention, portions of the first impression being broken away to expose the sheet.

2

FIG. 2 is a diagrammatic showing of a second method step, the first impression now being covered with a thin coating, portions of the coating and of the first impression being broken away.

FIG. 3 is a diagrammatic view showing the alternative provision of a thin film substituted for the coating, the film being shown partially laminated into position and portions thereof being broken away.

FIG. 4 is a diagrammatic plan view of the completed product, portions of the second impression and the intermediate coating or film and the primary impression being broken away.

FIG. 5 is a greatly enlarged fragmentary diagrammatic detail view in section on the line 5—5 of FIG. 4.

In the preferred practice of the invention, a multiple color press is used conventionally to print sequentially three or more colors to produce a multi-colored picture, upon a light-permeable base member, usually a web or sheet of commercially adequate body. The web or sheet may be entirely transparent if desired. In commercial practice, it is usually translucent. Ordinary paper is frequently used. For less opacity, I frequently use a well-known translucent paper such as Opaline or the like (Opaline being the trademark applied to a well-known example of a translucent material commonly used in the making of transparencies). Vinyl or the like is an example of a transparent material commonly used. While the number of colors is immaterial, I prefer to use any conventional multiple color press. For convenience of illustration, the "picture" is here represented by the four areas 8, 10, 12 and 14 which are delineated and shaded to represent four different colors.

Upon the completed impression thus printed by a multi-color press on the translucent or transparent base member, whether a web or sheet, I apply a light-permeable layer or ply 20 which is very thin and may be transparent but is normally translucent. Its function is primarily to provide a continuous coat over the multi-colored impressions previously made and thereby to provide a base for its successive similar impressions. Normally, this layer 20 will be white in color but it may be of so-called "neutral density" (which is a gray). As a preferred material for this purpose, I use a lithographic ink which is widely known in the industry under the name of "opaque white" and is compounded of linseed varnish, rosin and paraffin oil, titanium powder, magnesium powder, and blank fix powder. This coating is applied over the entire work and is very thin, approximating .06 micron. It only slightly obscures the first press lay down of a multi-color image with the result that the second multi-color lay down in the press will greatly increase the strength of the pigment for viewing by transmitted light without appreciably altering its normal appearance as viewed by reflected light.

While the work remains on the bed of the multi-color press, an impression, preferably identical with the first impression, is now printed upon the intermediate light-permeable layer in registry with the first impression. Normally, the same identical colors as well as the same identical outlines will be used. For the purposes hereof, the second "picture" is represented by the areas 28, 30, 32 and 34, these having lines indicating color and identical in delineation with the correspondingly lined areas 10, 12 and 14 of the first impression, with which the areas 28, 30, 32 and 34 are in exact registry. In FIGS. 4 and 5, reference character 20 has been used to identify the intermediate coating or laminate, it being understood that it is immaterial for the purposes of this diagrammatic disclosure whether the intermediate layer is a coating as at 20 or a laminate as at 200. For certain effects, it is possible to omit one or more colors used in the first printing.

The resulting product of the multi-color press operation will show a picture in brilliant color with full detail when viewed either with transmitted or reflected light. All colors will have substantially the same color density regardless of whether the picture is viewed by transmitted or reflected light, the effect being distinctly different in this regard from any previously known transparency.

In the preferred practice of the invention, a coating is used rather than a laminate. The coating is preferably applied by printing it upon the work but it may be applied in any manner, as by roller-coating or spraying or painting it directly upon the previously printed work. The coating may be transparent but preferably comprises material which will be translucent in effect. I have already stated as a preferred example "opaque white," which comprises a white pigment in an appropriate vehicle. As applied in a thin coating, it is not opaque but appropriately translucent. In the preferred practice of the invention, it will not completely obscure the originally printed picture, at least, when the picture is viewed in transmitted light. The intermediate layer is so extremely thin that if the two impressions have been printed in full register, as by a continuous or substantially continuous operation on a multi-color press, each will supplement the other to give an image which will be brilliant whether the picture is viewed in transmitted or reflected light.

I claim:

1. As a new article of manufacture, a multi-color press product which comprises a picture having a translucent base of sufficient thickness to be self-supporting and upon which are disposed a first series of at least three press impressions of differing colors, an extremely thin application of translucent material extending across said impressions, and a second series of identical impressions respectively of colors identical with the impressions of the first series and respectively superimposed in the same sense and in registry therewith on the same side of said base, whereby the colors of the first series impressions are intensified when the article is viewed as a transparency and are of substantially the same intensity as the colors disposed in the second series impressions when the article is viewed by reflected light.

2. An article according to claim 1 in which said application comprises a coating of translucent material which is sufficiently neutral to produce substantially no modification of the color of a color-press impression, the said coating being of the thickness of a single printing of ink.

3. A method of making a picture which produces substantially the same visual effect whether viewed as a transparency or by reflected light, said method consisting in placing upon a multi-color press a light permeable backing member having adequate body for handling as a transparency, the multi-color press-printing upon said body of a first series of at least three impressions of different colors to produce a color picture which can be viewed both as a transparency and by reflected light, making a thin application of light-permeable material across the impressions of the first series which constitute said picture, and multi-color press-printing on top of said material a second series of impressions identical in position and color and sense with color impressions of the first series, the impressions of the second series having increased density when viewed by transmitted light as compared with colored impressions which are not backed by like impressions of a previous series, the visual effect when viewed by transmitted light being substantially identical with the effect as viewed by reflected light.

4. A method according to claim 3 in which the step of making said application is a roller coating step.

5. A method according to claim 3 in which the step of making said application is a further press-printing step.
